CLAIM

The ornamental design for a display screen with transitional graphical user interface for medical imaging equipment as shown and described.

DESCRIPTION

FIG. 1 is a front view showing the display screen with transitional graphical user interface for medical imaging equipment showing a first image in the sequence;

FIG. 2 is a second image thereof;

FIG. 3 is a third image thereof;

FIG. 4 is a fourth image thereof; and,

FIG. 5 is a fifth image thereof.

The outermost broken lines depict a display screen in which the design is embodied and form no part of the claimed designed. The remaining broken lines illustrate portions of the graphical user interface that form no part of the claimed design.

The appearance of the transitional graphical user interface sequentially transitions between the images shown in FIGS.

(Continued)

1-5. The process or period in which an image transitions to another forms no part of the claimed design.

1 Claim, 5 Drawing Sheets
